INVENTOR:

MARGARET MACDONALD

PER
Andrew L. Chayen,

ATTORNEY

UNITED STATES PATENT OFFICE.

MARGARET MACDONALD, OF DAVENPORT, IOWA.

DESIGN FOR A CHOO-CHOO CAR.

60,870.

Specification for Design. Patented Apr. 18, 1922.

Application filed June 6, 1921. Serial No. 475,445. Term of patent 3½ years.

To all whom it may concern:

Be it known that I, MARGARET MACDONALD, a citizen of the United States, residing at Davenport, in the county of Scott and State of Iowa, have invented a new, original, and ornamental Design for a Choo-Choo Car, of which the following is a specification, reference being had to the accompanying drawing, forming part thereof.

The Figure 1 is a top plan view, and Fig.

2 is a side elevation of a choo-choo car showing my new design.

I claim:

The ornamental design for a choo-choo car as shown.

MARGARET MACDONALD.

Witnesses:

Mrs. VALBORG KNIEREN,
DAVID B. MACDONALD.
